UNITED STATES PATENT OFFICE.

JOHN WILSON BROWN, JR., OF PHILADELPHIA, PENNSYLVANIA.

DESIGN FOR A FRUIT-SEEDER DISK.

SPECIFICATION forming part of Design No. 29,030, dated July 12, 1898.

Application filed May 2, 1898. Serial No. 679,545. Term of patent 14 years.

To all whom it may concern:

Be it known that I, JOHN WILSON BROWN, Jr., a citizen of the United States, residing in Philadelphia, Pennsylvania, have invented 5 a new and useful Design for Seeding-Disks for Fruit-Seeders, of which the following is a specification.

My design for a seeding-disk for a fruit-seeder is clearly illustrated in the accompanying drawings, in which—

Figure 1 is a view of the disk, and Fig. 2 is a perspective view showing three of the teeth of the disk enlarged. Fig. 3 is a sectional view on the line 3 3, Fig. 1.

15 The essential feature of the design is the circular disk, having deep radial recesses around its periphery, said recesses being tapered, forming tapered teeth with flat ends.

20 The disk A is in the form of a ring having a central opening a, and around the periphery

of the disk are a series of tapered recesses b, forming tapered teeth d. The central lines of the teeth radiate from a common center x. The teeth are tapered from the base to the point, and the points are flat, so as to form angular edges. The throat of each recess is rounded at the base, as clearly indicated in the drawings.

I claim—

The design for a seeding-disk of a fruit-seeder as herein described and as shown in the accompanying drawings.

In testimony whereof I have signed my name to this specification in the presence of two subscribing witnesses.

JOHN WILSON BROWN, JR.
